(57) **CLAIM**

The ornamental design for a rotatable shelving unit for a cabinet, as shown and described.

DESCRIPTION

FIG. 1 is an upper side perspective view of the rotatable shelving unit for a cabinet showing my new design.

FIG. 2 is a lower side perspective view of the design of FIG. 1.

FIG. 3 is a top view of the design of FIG. 1.

FIG. 4 is a bottom view of the design of FIG. 1.

FIG. 5 is a left side view of the design of FIG. 1, with a right side view being essentially identical thereto; and,
FIG. 6 is a front view of the design of FIG. 1, with a rear view being essentially identical thereto.
